A CORPORATION OF DELAWARE.

INSULATED SUPPORT FOR INDUCTANCE COILS.

Application filed December 11, 1922. Serial No. 606,104.

Our invention relates particularly to insulated supports for mounting inductance coils for radio apparatus. One of the objects of our invention is to so mount the 5 conductor forming the coil that it is entirely exposed to air except at those places where it is in metallic contact with metal studs which in turn are in metallic contact with metal bushings which are secured to supports 10 of insulating material.

This invention is an improvement of the construction shown in our patent for insulated supports on induction coils No. 1,342,303. In the above mentioned patent, the 15 copper conductor forming the inductance coil in practice was usually secured to the slotted metal studs by means of soldering the connector to the stud. While this method was satisfactory with many sizes of coils, 20 there was some difficulty in applying it to other sizes and careful workmanship was required on the soldering so that the heat resulting from this operation did not loosen the studs or injure the insulating material. 25 In the present invention the metal studs are first soldered to the copper coil and then the studs are inserted in metal bushings in the insulating material and then secured in place as hereinafter described without requiring 30 any heat to be applied to the insulating material. Another advantage of the present invention is that by securing the metal studs to the coil at proper distances from each other, the coil will more readily take the 35 form of a true spiral or true helix, as the case may be, when the studs soldered to the coil are inserted in the insulated bushing. In the construction of the coil in accordance 40 with our patent mentioned above, considerable care had to be exercised in placing the coil in the slots so that the resulting spiral or helix would have a perfectly uniform shape and the spacing between the turns be accurate at all points on the coil.

45 Another object is to mount the conductor in such a manner as to permit it to radiate heat to a maximum degree, thereby providing for rapid cooling of the conductor. Another object is to so mount the conductor of the inductance coil that there will be no insulating material actually between the coils by reason of the provision of insulating mate-

rial only between the metal bushings in which are secured the metal studs to which the coils are connected, and thereby reduce 55 the distributed capacity of the coil.

Another object is to so construct a coil that the entire coil can be mechanically and electrically strong and the copper ribbon forming the coil be held positively in place 60 without requiring any soldered connections or heat to be applied with metal in contact with insulating material, and the coil to be so designed that one edge of it will be suitable for making contact with the sliding arm. 65

Another object is to so construct a coil mounting and coil winding that the complete structure is mechanically strong and in which there are no metallic parts except those which are in electrical contact with the 70 conductor forming the coil, and that these metallic parts are so secured to the insulating material that there will be no chance for brushing on these metallic parts through the 75 insulating material.

Other objects will appear from the hereinafter specifications and claims.

Referring to the drawings, in which similar reference characters indicate the same parts in the several views:

Fig. 1 is a view in section consisting of a portion of a tubular support provided with metal sockets for the reception of engaging studs.

Fig. 2 is a section on line 7—7 of Fig. 7. 85

Fig. 3 is a view in elevation of a copper wire or rod to which is secured contact studs of another form to engage the sockets or sleeves shown in Fig. 7.

Fig. 4 is an elevation of a wire or rod 90 provided with copper tubes for the reception of contact pins supported on the insulated mounting.

Fig. 5 is a section of an insulating tube 95 provided with contact pins similar in structure to the pins shown in Fig. 9 and adapted to engage the copper tubes of Fig. 10.

Fig. 6 is a section on lines d—d of Figs. 9 and 11.

In Figs. 1 and 5 we show a form of tubular insulating support C' which may be made out of any suitable insulating material, preferably "Electrose", in which the metal bushings B' are inserted into and ex-

panded or spun against the walls of the holes or openings D' in order to hold them tightly in place.

We find a wire rod preferably of copper 5 is much more readily manipulated or handled than a ribbon of metal, consequently, we provide a wire rod K' into which copper pins B² are inserted, and which are secured in place preferably by means of solder. These 10 pins have longitudinal slots X and Y extending through the same at right angles to each other, the portions of the pins on either side of the slots being expanded preferably by inserting a tool therein so that 15 the expanded pin will receive a tight fit in the socket or sleeve provided for the contact.

In Fig. 5 we show a tube C' similar to that shown, in Fig. 1 in which copper pins 20 B² such as shown in Fig. 3, and described with respect thereto, are rigidly mounted. These pins are designed to engage the copper tubes C² which are secured to the copper wire or rod K², the ends of the pins being inserted in the sockets V formed in the wire or rod, and the copper tubes are secured to the sockets preferably by means of solder to cause them to be permanently held 25 in the wire or rod.

30 As above described, the copper pins are

forced into the copper tubes and make a perfect contact because of the spring action of the ends of each of the pins.

We also provide ventilating openings D² and D³ through the tubes, as clearly shown 35 in Fig. 2. This same structure is applicable to the structure shown in Fig. 5.

Having thus described our invention what we claim as new and desire to secure by Letters Patent is:

1. A device of the type described which comprises, a hollow rod of insulating material having vent openings in its walls, pins mounted in said rod and extending outwardly therefrom, a conductor and hollow studs rigidly mounted on said conductor and fitting over said pins. 40

2. A device of the type described which comprises, a tubular rod of insulating material, studs mounted in and extending outwardly from said rod, said rod having bosses about said studs and vent openings in its walls, a conductor and hollow tubular pins rigidly mounted on said conductor and fitted over said studs, said studs having longitudinal slots and being tooled out about said slots to frictionally engage the inner wall of said hollow pins. 45
